INVALID LIFTING MEANS

Eva D. Bedard, Springfield, Mass.

Application January 20, 1948, Serial No. 3,215

1 Claim. (Cl. 5—85)

1

This invention relates to invalid lifting means, and has for one of its objects the production of a simple and efficient means for facilitating the lifting of an invalid to and from a bed with a maximum amount of ease and a minimum amount of inconvenience to the invalid or patient.

A further object of this invention is the production of a simple and efficient weight box which is carried by the main supporting shaft to act as a counterbalance for the weight of the patient or invalid carried on the stretcher.

Other objects and advantages of this invention will appear throughout the following specification and claim.

In the drawings—

Figure 1 is a perspective view of the lifting device and bed assembly;

Figure 2 is a perspective view of the lifting device with the bed removed;

Figure 3 is a perspective view of one of the standards and weight box supported thereby;

Figure 4 is a side elevational view of the weight box and a portion of the supporting standard therefor.

By referring to the drawings, it will be seen that the invalid-lifting means comprises a pair of spaced vertical standards 10 and 11. Each standard is supported upon a suitable base 12 having suitable casters 13 to facilitate moving of the device. The standards 10 and 11 are braced near the bottom by an intermediate bottom brace rail 14. A stretcher-supporting shaft 15 passes transversely through the upper ends of the standards 10 and 11, these upper ends constituting journals for the shaft 15. An enlarged gear 16 is secured near one end of the shaft 15 adjacent the standard 10 and a driving pinion 17 meshes with the gear 16 for rotating the gear 16 and shaft 15. A suitable operating crank 18 is secured to the gear 17 to drive this gear. A removable stop pin 20 is carried by the standard 10 and engages the crank 18 to prevent the crank 18 from swinging in one direction and to hold the stretcher 19 hereinafter described, in a selected elevated position. The bottom of the standard 10 which supports the gears 16 and 17 and the adjoining end of the rail 14 are braced by an inclined brace 21, as shown in Figures 1 and 2. A similar inclined brace 21 is located at the opposite end, as shown in Figure 2.

A pair of stretcher-suspending straps 23 and 24 are anchored at one end to the shaft 15, as shown in Figure 1. A buckle 25 of a conventional type is carried by each strap 22 and 23 intermediate the ends thereof. The stretcher 19 preferably is

2

formed of heavy cotton cloth, or other suitable flexible material and carries a pair of spaced stretcher poles 26 and 27 which pass through suitable casings which are formed by stitching the stretcher fabric along the side edges of the stretcher in the conventional manner.

Spreader boards 28 are fitted over the opposite ends of the poles 26 and 27 to hold the poles in spaced relation and to provide a stretcher of a desired width to support the patient or invalid placed thereon. The stretcher 19 is provided with a longitudinal slit 29 to facilitate the use of a bed-pan when the stretcher is placed upon the removable bed B. The free ends of the straps 23 and 24 pass around and under the ends of the poles 26 and 27, as shown in Figure 2, and the terminals of the straps are secured to the buckles 25 to suspend the stretcher 19 in a selected suspended elevation. The stretcher 19 may be raised by coiling the straps 23 and 24 around the shaft 15 as the shaft 15 is rotated through the operation of the crank 18. The stretcher 19 may be lowered by operating the crank 18 in the opposite direction to unwind the straps. The removable pin 20 may be placed in a proper position to hold the crank against swinging movement.

The stretcher 19 is adapted to be lowered upon the bed B and the poles 26 and 27 are pulled out from the casing 30 to permit the stretcher 19 to lie flat upon the bed B. The terminals of the straps 23 and 24 may be detachably fastened around the standards 10 and 11 in any desired manner to provide loops 31 to hold the straps out of the way of the patient or attendant.

To provide a suitable counterbalance for the weight of the patient or invalid upon the stretcher 19, while raising and lowering the stretcher, there is provided a novel weight box 32. This box 32 comprises a casing having a vertical notch 33 formed upon the rear face thereof in which the standard 11 snugly fits. This box 32 is slideable vertically upon the standard 11 and is held against removal from the standard 11 by means of the straps or plates 34 which span the notch 33 and extend across the rear face 35 of the standard 11. Suspending straps 36 are anchored at their upper ends, as at 37, to the outer end 38 of the shaft 15, and are adapted to be coiled about the shaft 15, as this shaft is rotated in one direction.

The lower ends 39 are clamped to the top of the box 32 by means of a cleat 40. Suitable bracing bolts 41 pass through the cleat 40 and the top and bottom of the box 32, to brace the bottom of the box and to assist in supporting the re-

movable weight bars 42 which bars are adapted to be placed in the box 32. Any desired number of bars may be placed in the box 32 depending upon the weight which is to be carried by the stretcher. The box 32 is provided with a front door 43 which may be opened and closed for the purpose of inserting or removing the weights 42. This weight box 32 will greatly facilitate the raising and lowering of the stretcher 19 since the box will freely slide up and down upon the standard 11, as the crank 18 is operated, and this box 32 will constitute a counterbalance for the stretcher and its occupant in the operation of the device.

An invalid or patient may be easily lifted to and from the bed B by means of the stretcher 19 and the operating mechanism above described. The stretcher 19 is placed upon the bed B under the patient and the poles 26 and 27 are placed in the casings 30. The spreader boards or members 28 are placed over the ends of the poles 26 and 27 and the straps 23 and 24 are secured as shown in Figure 2. The crank 18 is operated to raise the stretcher 19 and the pin 20 is properly placed against the crank 18 to hold the stretcher 19 in a set raised position. The bed B may be lifted away from the lifting device and the stretcher 19 may be manually lifted and detached from the lifting device to remove the occupant to a desired location.

The patient or invalid may be placed upon the bed merely by reversing the operation after the bed B is placed in the position shown in Figure 1, and the stretcher 19 is lowered upon the bed B. After the patient or invalid is placed upon the bed B, the bed may be lifted and removed away from the lifting device until it is again needed. Consequently, it is not necessary that the lifting device remain over the bed B while the bed is being used, since the bed is entirely separate from the lifting device.

Having described the invention, what is claimed as new is:

An invalid lifting means of the class described

comprising a plurality of standards, a shaft journaled upon and extending between the standards, a stretcher, flexible means secured at one end to the shaft and being adapted to be wound upon said shaft as the shaft is rotated, means for rotating said shaft as the shaft is rotated, the flexible means detachably engaging the stretcher for raising and lowering the stretcher as the shaft is rotated in a selected direction, means for locking the shaft against rotation to hold the stretcher in a selected elevated position, a counterbalance weight, weight-suspending flexible means suspending said weight from said shaft, said counterbalance weight comprising a hollow box, removable weight members carried within said box, said box having a vertical notch in its inner side nearest the stretcher, one of said standards being substantially square in cross-section and fitting vertically in said notch, said last mentioned standard fitting snugly within the notch and the standard being flush with one side of the box, retaining members spanning said notch and the last mentioned adjoining standard for retaining said box in snugly fitting sliding vertical relation relative to the last mentioned standard, and anchoring means engaging the weight-suspending flexible means and extending through the bottom of said box.

EVA D. BEDARD.
